(57) **CLAIM**

The ornamental design for a bandsaw blade grinding apparatus mounting plate, as shown and described.

DESCRIPTION

FIG. 1 is a front perspective view of a bandsaw blade grinding apparatus mounting plate according to our new design;

FIG. 2 is a front view thereof;

FIG. 3 is a rear view thereof;

FIG. 4 is a top view thereof;

FIG. 5 is a bottom view thereof;

FIG. 6 is a right side view thereof, a left side view of the bandsaw blade grinding apparatus mounting plate being a mirror image of the right side view; and,

FIG. 7 is a rear perspective view.

The broken line showing of standoff pads in FIGS. 3 through 7 is for illustrative purposes only and forms no part of the claimed design.
